MANUFACTURE OF THICK-SOLED OR
PLATFORM SHOESFred L. Ayers, Watertown, Mass., assignor to
Brown Company, Berlin, N. H., a corporation
of Maine

Application May 11, 1938, Serial No. 207,298

6 Claims. (Cl. 12—146)

This invention relates to the manufacture of thick-soled or so-called platform shoes. While not limited thereto, it deals more especially with platform shoes made by the cement-process of 5 shoemaking.

Thick-soled or platform shoes for women are made essentially as ordinarily, excepting that a comparatively thick layer or mid-sole, herein-after termed the platform sole, is inserted or 10 added between the insole and outsole of the shoe. Such added sole not only makes possible a finished shoe with an attractive edge or trim thereon but, in the case of a short-statured woman, serves to increase her height appreciably. There 15 is usually, however, the decided objection to a platform shoe in that it does not, on account of the thickness of its platform sole, flex as readily as is desired at its forepart or ball portion. This lack of desired flexibility in the forepart, which 20 exists even when comparatively flexible material is used for the platform sole, has stood in the way of a much larger vogue for the platform shoe.

The main objective of the present invention is to achieve the desired flexibility in the forepart 25 of a platform shoe whose platform sole is of considerable thickness, for instance, of a thickness much greater than the usual outsole. While part of the desired flexibility may be realized by using as the platform sole comparatively flexible 30 material, such as "Onco" or its equivalent (i. e., artificial leather consisting of bonded plies of a rubber-impregnated felt or paper web), and still more flexibility realized by slashing the platform sole transversely at its forepart, as on its face 35 against which the outsole is secured, yet these expedients, neither singly nor conjunctively, conduce to a shoe of the desired flexibility at its forepart. This lack of flexibility is attributable in substantial measure to the tendency for the outsole, on account of the considerable thickness of 40 the platform sole, to slide or creep inwardly of the toe portion of the thick platform sole when the forepart of the shoe is flexed; but, inasmuch as the outsole is secured to the platform sole so 45 firmly that no such sliding or creeping movement is possible, a strong resistance is imposed against flexure of the forepart of the shoe, for instance, the normal flexure incident to comfortable walking with the usual or normal shoe.

In accordance with the present invention, the 50 resistance to flexure of a composite sole structure comprising an outsole and a platform sole is avoided in the finished shoe by preliminarily uniting such soles, as with suitable cement, while their foreparts are in suitably preflexed condition,

that is, while their foreparts are preflexed to an angle or curvature approximating or slightly more than the maximum angle or curvature of flexure occasioned in the course of use of the finished shoe to which the composite structure is 5 subsequently secured. This means that the outsole has already been permitted to slide or creep inwardly relative to the platform sole to the extent that it would otherwise tend to slide or creep but would be prevented from so doing in a platform shoe as heretofore made. The composite platform and outsole structure hereof thus acquires at its forepart a curvature corresponding to the curvature that is to be assumed thereby in the finished shoe when the forepart of the shoe 15 is flexed to approximately maximum or slightly more than the maximum curvature in ordinary use. By providing a platform sole of appropriate stretchability and/or in appropriately slashed condition, it is possible readily and permanently 20 to restore the composite preflexed sole structure, as during its securement to the lasted shoe-upper assembly, to its normal shape on the shoe, that is, to provide the normal or substantially flat shoe-sole forepart. Because the composite sole structure has thus already been conditioned or "broken in" for flexing at its forepart, the finished shoe 25 exhibits the desired ready or substantially normal flexibility at its forepart.

With the foregoing and other features and 30 objects in view, the invention hereof will now be described with particular reference to the accompanying drawing, wherein,

Figure 1 depicts in perspective a platform sole such as is useful for the purposes hereof, the 35 usual edge-trim or edge-binder fabric thereof being removed for sake of clarity at the toe portion.

Figure 2 represents a longitudinal section through a sole-preflexing last with the composite 40 platform sole and outsole structure appropriately conformed to the last bottom and with such soles cemented together.

Figure 3 is a section through the composite sole structure after its removal from the preflexing or 45 preshaping last.

Figure 4 represents a transverse section through the forepart of the lasted shoe-upper assembly and the composite sole structure just 50 before the latter has been cemented to the insole and the over-lasted shoe upper margins.

Figure 5 is a side elevation of the lasted shoe-upper assembly with the composite sole structure cemented thereto and undergoing the pressure of 55

the usual inflated rubber bag for holding the sole structure in place until the cement has set.

Figure 6 illustrates the finished platform shoe on the foot of the wearer.

5 Figure 7 is a fragmentary plan view of a sole-preflexing base mold on which a number of preflexed and preshaped composite sole structures may be simultaneously produced.

10 Figure 8 is a section through the mold of Figure 7 immediately after the upper or presser mold has been raised from the preflexed and preshaped composite sole structures.

15 The platform sole 10 shown in Figure 1 may consist of a number of plies of a rubber-impregnated felt or paper web in facially bonded relationship. Thus, it may consist of the artificial leather material known on the market as "Onco," which material consists of an absorbent paper web or base, such as a loosely felted web of refined wood pulp, that has been impregnated with a rubber latex composition and then dried. A number of the dried, latex-impregnated webs may be facially bonded together, as by rubber latex, into a plied structure, for instance, one 20 of about $\frac{1}{4}$ to $\frac{1}{2}$ " thickness and especially suitable for use as the stock for the platform sole hereof by reason of its comparatively high flexibility and high internal ply strength. It is desirable that the outer or lower face of the platform sole 10 be slashed transversely at closely spaced intervals at its ball zone, as on a plurality of lines of slash 11, which may occur at intervals of, say, about $\frac{1}{4}$ ", and extend deeply into the sole, say, to approximately half its thickness. The slashed area may commence at approximately the front shank line and leave off at the toe. As ordinarily, an edge-trimming or edge-binding strip 12 of suitable fabric, such as shoe-upper leather or lacquer-finished cloth, may 25 be cemented all around the sole edge with its marginslapping and adhesively united to both sole faces. In cementing the strip 12 to the sole edge, as by the usual continuous strip-cementing machine, the operator preferably flexes the sole 30 10 to approximately the configuration to be assumed thereby upon its being preflexed and preshaped, as shown in Figure 2, thereby minimizing the formation of wrinkles in the cemented strip when the edge-trimmed sole undergoes the preflexing and preshaping operation.

35 The edge-trimmed platform sole 10 is placed on a last 13 whose configuration may be substantially similar to that of the last on which the shoe is made, excepting that its bottom forepart 13a has an angularity or curvature approximating or slightly more than the maximum flexure angularity or curvature ensuing in the forepart of the finished shoe upon normal wear. The heel portion of the sole 10 may be fixed to 40 the last, as by a tack 14, whereupon a suitable cement, such as the usual pyroxylin cement used in making cement-process shoes, may be applied to the sole 10 as a thin coat 15 from its back shank-line to its very tip; and an ordinary leather outsole 16, whose shape substantially matches that of the sole 10, may be similarly daubed with the cement on its face to be applied to the sole 10. The superposed, substantially coinciding soles are then permanently united into 45 a composite structure on the last 13 while they are being pressed, as by the usual inflated rubber bag used in cement shoe manufacture, into conformity with the bottom of the last 13 and maintained in such conformity until the cement has 50 set or hardened.

Upon removal from the last, the prefabricated, composite sole structure has the longitudinal curvature or configuration illustrated in Figure 3. It might be noted that the cuts or slashes 11 in the outer face of the platform sole 10 facilitate 5 the flexing and conformation of the composite sole structure to the bottom of the last 13. Indeed, they permit the outer layers of the platform sole to take on readily at the forepart the desired preflexed contour, since they open up, 10 as indicated in Figure 2, to provide the necessary give of the outer layers without need for rupturing or stretching such layers, as would be necessary in their absence; and they also make possible the desired ready subsequent restoration of 15 the forepart of the platform sole to flat normal condition when the composite sole structure is united to the bottom of the lasted shoe-upper assembly. As appears in the drawing, the platform sole may be about twice as thick as the 20 outsole, whose thickness may, as ordinarily, be about $\frac{1}{8}$ of an inch and consist of ordinary sole leather.

25 The preflexed and preshaped composite sole structure may then be secured to a shoe-upper assembly lasted, as customarily, for cement-process shoe manufacture. Thus, as shown in Figure 4, a last 17 may carry the completed shoe-upper assembly 18 whose upper margins 19 are over-lasting and secured, as by cement and/or 30 tacks or the like, to the insole 20 and are appropriately trimmed for application of the sole structure thereto. If desired, the over-lasting margins of the shoe upper and the insole may be suitably roughened or abraded, as usual, preparatory to the application thereto of a coat 9 of cement for bonding the composite sole structure thereto from the heel end to the toe end. After thus applying cement to the bottom of the lasted 35 shoe-upper assembly and, if desired, also as a 40 coat 8 to the inner face 21 of the composite sole structure, the composite sole structure is placed on the cement-coated bottom of the shoe-upper assembly and the sole structure is, as indicated in Figure 5, pressed into conformity with the 45 bottom of the shoe-upper assembly and the bottom of the shoe last, as by the uniform pressing action of the usual inflated rubber bag 22 well known to those skilled in the art. It will be appreciated that, because the shank and heel portions of the composite sole structure have been preshaped to the curvature to be assumed thereby in the finished shoe, no trouble whatever is 50 encountered in conforming these portions of the composite sole structure to the shape of the last for the finished shoe; and the preflexed forepart of such structure is also readily pressed to the desired flat condition against the forepart of the insole 20 and the over-lasting shoe-upper margins 19, particularly as the inner and outer layers of the platform sole readily readjust themselves to a flat condition at the forepart as does the outsole. The composite sole structure is thus 55 kept pressed in cemented relationship against the bottom of the lasted shoe-upper assembly until the cement has set and the shoe is ready for finishing operations, including edge-trimming and finishing of the outsole, securing and finishing of the shoe heel, etc. The heel portion of the outsole is shown in Figure 5 as being split at its heel portion, as ordinarily, into two 60 layers, the outer layer 23 of which may be cemented as a protective covering to the breast portion of the heel 24 in the finished shoe shown in Figure 6. The splitting of the heel portion 65

of the outsole may be accomplished at any suitable stage of the method hereof, for instance, either before or after the outsole has been bonded to the platform sole.

5 The particular method hereinbefore described is subject to considerable variation. For instance, the platform sole may be slashed transversely at the ball zone of its inner face (i. e., the face lying next to the insole) rather than 10 being slashed at its outer face; and such slashing is also advantageous for realizing the desired flexibility in the finished platform shoe and also for realizing the desired preflexed conformation of the composite or cemented platform sole and 15 outsole structure to the bottom of the preflexing last, since the inner layers of the platform sole, especially with V-shaped slashes therein, may be freely flexed in the absence of undue and undesirable crowding and wrinkling thereof such as 20 tends to occur when such layers undergo compression in unslashed condition under the flexure incident to conformation to the bottom of the preshaping last. It is hence usually preferable in the practice of the instant invention to slash 25 the platform sole transversely at the ball zone on both its inner and outer faces, the slashes preferably taking the form of V-shaped notches extending into the body of the platform to a depth of, say, one-quarter the thickness of such sole. 30 The transverse lines of slash on the outer face of the platform sole may be desirably staggered relative to the transverse lines of slash on the inner face of such sole (with intervals, of say, about $\frac{1}{4}$ " between the slashes on each face), in 35 which latter case each set of slashes may be of a depth about one-half the thickness of the platform sole. Again, it might be noted that the union of the platform sole with the outsole while 40 their foreparts are in the desired preflexed condition on the preflexing last may be accomplished by expedients other than or additional to cement, for instance, stitches and/or tacks or the like. However, the union of the platform sole and the outsole with their foreparts in desirably 45 preflexed condition is most readily and economically accomplished with cement, as already described; and, when a stitched union of such soles is desired, the stitching is preferably done after the soles of the composite sole structure 50 have been cemented together in desirably preflexed condition, as illustrated in Figure 3. In such latter case, the cement may be regarded as the medium for uniting the soles into a composite structure of the desired preliminary or 55 temporary configuration; and the stitching may be regarded as the means for ensuring a permanent union of the soles in the finished shoe.

The method hereof fits nicely into the scheme of usual cement-shoe manufacture, for the last 60 13 may replace every alternate last of the endless shoe-last conveyor used in making "Compo" shoes. In other words, one last of the conveyor may deliver to an operator the completed shoe-upper assembly and the next last deliver a composite sole structure with its soles cemented together in preflexed and preshaped condition. The operator may cement the composite sole structure to the bottom of the lasted shoe-upper assembly; and the lasted shoe-upper assembly 65 together with the sole structure applied thereto then transferred to another endless conveyor on which the sole structure is kept, as by an inflated rubber bag, in pressed conformity with the bottom of the lasted shoe-upper assembly until the cement sets or hardens. If desired, however, one 70

last-conveyor may simply carry the preflexing lasts 13 on which the composite sole structures hereof are produced in properly preflexed and preshaped condition for securement to the bottom of the lasted shoe-upper assemblies; and another last-conveyor may carry the lasted shoe-upper assemblies to whose bottoms the preflexed and preshaped composite sole structures hereof are cemented and conformed, as already described.

10 In some instances, the composite sole structure may be formed up in the desired preflexed and preshaped condition as a plurality of units in a suitable mold, as illustrated in Figures 7 and 8. The base mold 25 may, in such case, have a configuration similar to that of the bottom of the last 13. A plurality of composite sole structures may be produced by cementing the edge-trimmed or edge-bound and preferably slashed platform soles in flat condition to the outsoles and then 15 placing the flat composite structures 26 on the base mold 25. Thereupon, the upper or presser mold 27 may be brought down against the composite sole structures to unite and press them permanently to the configuration of the base 25 mold. After the composite sole structures have set in the desired preflexed or preshaped condition, the presser mold 27 may be raised and the resulting structures are ready to be united, as 20 already described, to lasted shoe-upper assemblies. 30

The invention hereof is not limited to the use of "Onco" or similar artificial leather as the platform sole material. Thus, any other suitable material, preferably of greater flexibility and 35 stretchability than sole leather, such as felts or paddings, sheeted cork compositions, etc., may be used as the platform sole material; and, in some instances, the platform sole need not extend from the toe end to the heel end of the shoe but 40 may terminate short of the heel end, say, at the front shank line or at the back shank line. In other words, the ornamental and platform or height-increasing effect of a platform sole is usually desired only in the forepart of a shoe, in 45 consequence of which the platform sole may be essentially only a forepart member. Again, the invention hereof is applicable to other than cement-process shoes, for instance, to McKay shoes, Littleway lockstitch shoes, welt shoes, etc. 50 In other words, the composite sole structure, inclusive of the platform sole and the outsole, with its sole cemented together or otherwise united and preflexed at their foreparts may, as hereinbefore described, be secured or fastened to the 55 bottom of a lasted shoe-upper assembly designed for any desired make of shoe, that is, a shoe to which the composite sole structure hereof is cemented or stitched. The essence of the present invention hence lies in the preflexing of the foreparts of the platform sole and the outsole, the bonding or cementing of the soles in such preflexed condition, and their subsequent conformation to the shape of the substantially flat-bottomed forepart of the lasted shoe-upper assembly 60 in the course of their securement by cementing, stitching, or other suitable means to the bottom of such assembly. It is thus possible by the present invention to realize readily and economically the desired flexibility in the forepart of a platform shoe. 70

I claim:

1. A composite sole structure for a platform shoe comprising an outsole and a markedly thicker platform sole in facially cemented rela- 75

- tionship with their foreparts flexed to a curvature to be assumed thereby upon flexing of the forepart of the finished shoe during its normal wear, said platform sole being transversely slashed at its ball zone.
2. A composite sole structure for a platform shoe comprising a leather outsole and a markedly thicker platform sole in facially cemented relationship with their foreparts flexed to a curvature to be assumed thereby upon flexing of the forepart of the finished shoe during its normal wear, said platform sole being of a material more flexible than the leather outsole and being transversely slashed at its ball zone.
3. A composite sole structure for a platform shoe comprising a leather outsole and a markedly thicker platform sole in facially cemented relationship with their foreparts flexed to a curvature to be assumed thereby upon flexing of the forepart of the finished shoe during its normal wear, said platform sole being essentially multi-ply rubber-impregnated paper web material of greater flexibility than the leather outsole and being transversely slashed at its ball zone.
4. A prefabricated, composite sole structure for a platform shoe comprising a leather outsole and a markedly thicker, substantially coinciding platform sole in facially cemented relationship with their foreparts flexed to a curvature to be assumed thereby upon flexing of the forepart of the finished shoe during its normal wear, said platform sole consisting of material more flexible than the leather outsole and being transversely slashed at its ball zone and the edge of said platform sole being protected by strip material lapping its faces and cemented thereto.
5. In a method of making a platform shoe, those steps which comprise providing a leather outsole and a platform sole of greater thickness and more flexible material than said outsole, slashing the platform sole transversely at its ball zone, and simultaneously cementing together and conforming said outsole and platform sole in superposed relationship to the bottom of a last whose bottom shape is substantially similar to that of the finished shoe excepting that its forepart is of a curvature corresponding to the flexed curvature to be assumed by the composite sole structure upon flexing of the forepart of the finished shoe during its normal wear.
6. In a method of making a platform shoe, those steps which comprise providing a leather outsole and a platform sole of greater thickness and of more flexible material than said outsole, slashing the platform sole transversely at its ball zone, cementing to the edge of said platform sole a covering strip in lapping relationship to its faces, and simultaneously cementing together and conforming said outsole and platform sole in superposed relationship to the bottom of a last whose bottom shape is substantially similar to that of the finished shoe excepting that its forepart is of a curvature corresponding to the flexed curvature to be assumed by the composite sole structure upon flexing of the forepart of the finished shoe during its normal wear.

FRED L. AYERS.
